Primary Examiner — Kendra Leslie Hamilton*(74) Attorney, Agent, or Firm* — Nelson Mullins Riley & Scarborough LLP(57) **CLAIM**

The ornamental design for an oral-motor chew tool, substantially as shown and described.

DESCRIPTION

FIG. 1 is a top, front, left perspective view of an oral-motor chew tool, showing my new design in condition of use; FIG. 2 is a right side elevation view of the oral-motor chew tool of FIG. 1;

FIG. 3 is a left side elevation view thereof;

FIG. 4 is a front elevation view thereof;

FIG. 5 is a back elevation view thereof;

FIG. 6 is a top plan view thereof; and,

FIG. 7 is a bottom plan view thereof.

In the drawings, the area inside the broken lines on the oral-motor chew tool forms no part of the claimed design. The broken lines showing a pencil in FIG. 1 depict environmental structure that forms no part of the claimed design. All broken lines form no part of the claim.
